UNITED STATES PATENT OFFICE.

GEORGE E. DRESSER, OF NIAGARA FALLS, NEW YORK, ASSIGNOR TO THE CARBO-RUNDUM COMPANY, OF NIAGARA FALLS, NEW YORK, A CORPORATION OF PENNSYLVANIA.

ABRASIVE STONE.

Application filed September 17, 1924. Serial No. 738,161.

The present invention relates to abrasive stones and particularly to abrasive stones for dressing or sharpening vibrator or contact points in automobile ignition systems.

5 In the magneto system the contact points are made of platinum and can be dressed with a thin file especially made for such purpose. In the battery system, however, the contact points are made of tungsten steel and a file 10 has practically no effect on them. Therefore, the only way to dress them is with an abrasive stone.

Abrasive stones have been put out for this purpose having a tapered shape and tapering down to about $\frac{1}{16}$ " in thickness. These stones 15 can only be used on the extreme point and when this is worn out the stone is of no further use and is thrown away. To overcome this difficulty it has been proposed to 20 make the stones with a uniform thickness of about $\frac{1}{16}$ " throughout their length. The trouble with an abrasive stone of this character is that it is very fragile and is soon broken in use or when thrown around in a 25 tool kit.

By the present invention I overcome this difficulty by providing the abrasive stone of uniform thickness with a metal reinforcement along one edge thereof. This reinforcement 30 is made thin enough so as not to interfere with the insertion of the stone into different types of mechanism and it covers only a small part of the width of the stone. This reinforcement, running substantially the full 35 length of the stone, enables it to be thrown about or dropped on the floor with small liability of the stone breaking. If a piece is broken off of the end of the stone, the metal reinforcement can be cut off and the stone 40 can then be used like a new stone.

This type of stone is particularly advantageous because it can be inserted and operated with any of the usual types of vibrator mechanisms and it is possible with this stone 45 having parallel sides and uniform thickness, to dress off two abutting contact points at the same time, that is, with one insertion of the stone. This saves considerable time as it is possible with this reinforced stone to dress 50 two points in from two to three minutes where previously it took from five to seven minutes.

In the accompanying drawings wherein I have illustrated a preferred embodiment of my invention—Figure 1 is a perspective view

of a stone having a reinforcement along one 55 edge in accordance with my invention;

Figure 2 is a transverse section of the stone shown in Figure 1; and

Figure 3 is a perspective of the reinforcement removed from the stone. 60

The stone 2 is preferably made of carbo-rundum and of uniform thickness of about $\frac{1}{16}$ " throughout its length. The stone may be made of any convenient length and is made relatively narrow. Along one of the longitudinal edges of the stone I provide a metal reinforcement 3 extending substantially the full length of the stone. This reinforcement is preferably made of thin sheet metal bent into the form of a channel so as to grip the 70 opposite faces of the stone. The friction between the reinforcement and the faces of the stone will ordinarily hold the reinforcement on the stone but, if desired, the reinforcement may be additionally secured by means 75 of cement. The reinforcement is made sufficiently thin so as not to interfere with the use of the stone and it is made to extend only over a small portion of the width of the stone on the opposite faces thereof. 80

This reinforcement prevents breaking or chipping of the stone under ordinary conditions and in case an end portion of the stone does become broken from the main body of the stone the projecting portion of the 85 metal reinforcement can be readily cut off and the stone used like a new stone.

While I have shown a preferred manner of reinforcing the stone it will be understood that the invention is not limited to the exact 90 form shown but that it may be modified within the scope of the appended claims.

I claim:

1. As a new article of manufacture, an abrasive stone for use as a file for dressing the contact points of automobile ignition systems, consisting of a strip of abrasive stone of substantially uniform thickness of about $\frac{1}{16}$ inch throughout its length and which is thin enough to pass between the contact points 95 of such ignition systems but not thick enough to withstand the use to which it is to be put without breaking, and a sheet metal reinforcing member of channel form closely fitting over one edge of the strip along substantially 100 its full length, said reinforcing member extending over a small portion only of the width of the stone and being sufficiently thin so 105

as not to interfere with the use of the stone in dressing the contact points of automobile ignition systems.

2. As a new article of manufacture, an abrasive stone for use as a file for dressing the contact points of automobile ignition systems, consisting of a strip of abrasive stone of substantially uniform thickness and thin enough to pass between the contact points of such ignition systems and a sheet metal reinforcing member of channel form closely

fitting over one edge of the strip along substantially its full length, said reinforcing member extending over a small portion only of the width of the stone and being sufficiently thin so as not to interfere with the use of the stone in dressing the contact points of automobile ignition systems. 15

In testimony whereof I have hereunto set my hand.

GEORGE E. DRESSER.
